UNITED STATES PATENT OFFICE.

JOHN WILKINSON, OF SYRACUSE, NEW YORK, ASSIGNOR TO H. H. FRANKLIN MANUFACTURING COMPANY, OF SYRACUSE, NEW YORK, A CORPORATION OF NEW YORK.

GEARING.

No. 825,438.

Specification of Letters Patent.

Patented July 10, 1906.

Application filed August 29, 1902. Serial No. 121,454.

To all whom it may concern.

Be it known that I, JOHN WILKINSON, of Syracuse, in the county of Onondaga and State of New York, have invented a certain new and useful Gearing, of which the following is a specification.

My invention has for its object the production of a gearing which is especially applicable for transmitting power from the engines or other motors of automobiles to the propelling-wheels thereof, and is particularly simple in construction, economical in manufacture, and durable and efficient in use; and to this end it consists in the devices and combinations hereinafter set forth and claimed.

Figure 1 is a sectional view of a preferable embodiment of my gearing, portions of the driving member being broken away and indicated by dotted lines and part of an engine-frame being shown by dotted lines. Figs. 2 and 3 are sectional views taken on lines 2 2 and 3 3, Fig. 1. Fig. 4 is a sectional view taken on line 4 4, Fig. 1. Fig. 5 is a detail view of a portion of the case.

25 The preferable embodiment of my gearing comprises, essentially, a case A, rotatable driving and driven members B C, a gear D, a support E, planetary gears F G, means for limiting the rotation of the gear D and the support E, and means for connecting the support E to the driving member B.

The case A is here illustrated as consisting of a main body a, which supports a movable section a' and is mounted on the frame A' of the engine or other motor for actuating the driving member B. Said main body a consists of parts or divisions a² a³, removably secured together by suitable fastening means, as bolts, (not shown,) which permit the part 35 or division a² to be removed from the part or division a³ when access to the interior of the case A is desired. The main body a is usually provided with an outer or peripheral wall and side walls having substantially central openings a⁴ a⁵, one of the side walls being formed with an annular groove a⁶ in the inclosing wall of the opening a⁵ and being provided with a chamber a⁷, projecting from the opening a⁵ and having an internal hub a⁸. The 45 movable section a' is journaled on a bearing-surface formed on the periphery of the main body a concentric with the driving and driven members B C and is provided with a

tubular cam a⁹, projecting within the opening a⁴, and with suitable means, as slots a¹⁰, having inclined portions or camways a¹¹ for coöoperating with means, as pins a¹², fixed to the main body a for forcing the section a' endwise during the movement of said section on its axis.

55 The driving member B is here illustrated as a crank-shaft extended within the case A, journaled in a part of the frame A' (not illustrated) and in the hub a⁸ and provided with gears b b' of unequal diameter and a support 60 b², detachably secured to said member B by keys or other desirable means. Said gears b b', which form, essentially, parts of the driving member B, are provided with hubs of less diameter than their toothed surfaces, 65 the gear b' of larger size being generally mounted on the hub of the gear b. The inner face of the support b² is engaged with the contiguous end faces of the hubs of the gears b b', and the outer face of said support is provided with a hub closely fitting within the cam a⁹ and with a spindle b³ and an engaging arm b⁴, arranged on opposite sides of the cam a⁹, the engaging arm b⁴ being formed of angular cross-section.

70 As here shown, the driven member C consists of a main body c, loosely and detachably mounted on the hub a⁸ and formed with a flange c' and a disk c², detachably mounted on the main body c, fixed to the flange c' and provided with a series of spindles c³, extending within the gear D, each of the spindles c³ being arranged eccentric to the axis of the driven member and formed integral with said member and being unsupported at corresponding ends. A suitable collar c⁴ projects into the annular groove a⁶ of the case A and coöperates with the flange c' to close the portion of the opening a⁵ not occupied by the driven member C and prevent the escape of 75 lubricant from within the case A.

80 The gear D is revoluble relatively to the driving and driven members B C and preferably consists of a substantially ring-shaped part d, formed with an internal-toothed surface, a hub d', mounted on the hub of the gear b and formed with a flange d², and a disk d³, mounted on the hub d', fixed to the flange d² and having its peripheral face engaged with the intermediate portion of the 85 internal toothed surface of the part d. The 90

teeth of the gear D thus project on opposite sides of the disk d^3 . As best seen in Fig. 1, the support E is revoluble relatively to the driving and driven members, and its central portion is arranged at the outer side of the support b^2 . One side of the support E is provided with a flange e , projecting toward the contiguous side wall of the main body a of the case A and encircling the support b^2 , and the other side of said support E is provided with a hub e' , extending within the gear D and detachably mounted on the hub of the gear b' , and with a series of spindles e^2 , also extending within the gear D, each of the spindles e^2 being arranged eccentric to the axis of the support and formed integral with said support and being unsupported at corresponding ends.

The planetary gears F G are of unequal diameter, are loosely mounted on the spindles e^2 at opposite sides of the disk d^3 , are normally detachable from said spindles, and are respectively connected to the gears b b' D, being here shown as directly in mesh with said gears b b' D. The opposing side faces of the gears F G are preferably engaged with opposite sides of the disk d^3 in order that said disk may normally prevent the movement of these gears endwise from their supporting-spindles e^2 .

The means for limiting the rotation of the gear D and the support E consists of split friction-rings h h' of similar construction, interposed between contiguous surfaces of the case A and the parts D E and having contiguous ends prevented from movement relatively to the case A by suitable means, as screws h^2 , and their other ends provided with slots for receiving the heads of additional means, as screws h^3 , and with slots for receiving the inner ends of rocking engaging means, as levers h^4 , which are adjustable on the case A and clamp the friction-bands h h' upon the peripheries of the gear D and the flange e . One of the levers h^4 may be provided with a roller h^5 , engaged by a cam h^6 on the movable section a' , and the other lever h^4 may be actuated by a link or other power-transmitting means (not illustrated) suitably connected to said lever for rocking the same on its pivot.

As usually constructed the means for connecting the support E to the driving member B consists of a split friction-ring i , arranged within the flange e and having its intermediate portion formed with a cut-out i' for receiving the engaging arm b^4 and an expander i^2 , loosely and detachably mounted on the spindle b^3 and having one end movable between the separated ends of the friction-ring i for forcing said ends apart and engaging the ring i with the inner face of the flange e and having its other end engaged with the cam a^9 and movable outwardly thereby when the movable section a' is forced endwise.

In the operation of my gearing the section a' is moved in one direction until the camways a^{11} force the cam a^9 inwardly and moves the expander into its operative position, thus locking the supports b^2 E together and compelling the driven member to rotate forwardly at the same speed as the driving member. When it is desired to rotate the driven member forwardly at reduced speed, the movable section a' is reversely turned for forcing the cam a^9 into its inoperative position and causing the cam h^6 to actuate the corresponding lever h^4 for clamping the friction-band h upon the gear D and holding said gear stationary, whereupon the planetary gears F coöperate with the gears b D to effect the desired rotation of the driven member. The reverse movement of the driven member C is effected by moving the section a' of the case A on its axis until the cam h^6 is withdrawn from its operative engagement with the corresponding lever h^4 to permit the friction-band h to release the gear D and by actuating the other lever h^4 to clamp the friction-band h' upon the support E, thus holding said support stationary and compelling the gears b' G to rotate the gear D in a direction opposite to that of the driving member, which movement is transferred by the gears F b to the driven member C. As will be obvious to those skilled in the art, the parts of my gearing within the case A may all be readily detached from each other after the removal of the part or division a^2 , and consequently a gear broken or unduly worn may be readily replaced without removing rivets, pins, or other means.

The construction and operation of my gearing will now be readily understood upon reference to the foregoing description and the accompanying drawings, and it will be apparent that more or less change may be made in the construction and arrangement of the component parts thereof without departing from the spirit of my invention.

Having thus fully described my invention, what I claim as new, and desire to secure by Letters Patent, is—

1. The combination of a rotatable driving member, a driven member consisting of a main body formed with a flange, and a disk detachably mounted on the main body and fixed to the flange, said disk being provided with an integral spindle arranged eccentric to the axis of the driven member and projecting from one face of the disk, a gear revoluble with the driving member, a second gear revoluble relatively to the driven member, a gear journaled on said spindle and connected respectively to the former gears for transmitting motion to the driven member and means for limiting the rotation of said second gear, substantially as and for the purpose specified.

2. The combination of rotatable driving and driven members, a gear revoluble with

- the driving member, a second gear revoluble relatively to the driven member and comprising a substantially ring-shaped part formed with an internal-toothed surface, and 5 a disk supported on the driving member and having a peripheral face engaged with the internal-toothed surface of said part, a planetary gear revoluble with the driven member and connected respectively to the former gears 10 for transmitting motion to the driven member and means for limiting the rotation of said second gear, substantially as and for the purpose described.
3. The combination of rotatable driving and driven members, a gear revoluble with the driving member, a second gear revoluble relatively to the driven member and consisting of a substantially ring-shaped part formed with an internal-toothed surface, a 15 hub supported by the driving member and formed with a flange, and a disk mounted on said hub and fixed to the flange, the disk having a peripheral face engaged with the internal-toothed surface of said part, a spindle arranged eccentric to the axis of the driven member and having one end supported by the driven member and its other end unsupported, a gear journaled on the spindle and connected respectively to the former 20 gears for transmitting motion to the driven member, a side face of said last gear engaging the contiguous face of said disk for holding the gear on the spindle, and means for limiting the rotation of said second gear, substantially as and for the purpose described.
4. The combination of rotatable driving and driven members, a pair of gears revoluble with the driving member, a second gear revoluble relatively to the driven member 25 and comprising a substantially ring-shaped part and a disk for supporting the ring-shaped part mounted upon one of the rotatable members, said ring-shaped part having internal teeth disposed on opposite sides of the disk, planetary gears arranged on opposite sides of the disk and connected respectively to the gears revoluble with the driving member and to said second gear, one planetary gear being connected to the driven member, means for controlling the rotation of the other planetary gear, and means for limiting the rotation of said second gear, substantially as set forth.
5. The combination of rotatable driving and driven members, a pair of gears revoluble with the driving member, a second gear revoluble relatively to the driven member and comprising a substantially ring-shaped part formed with an internal-toothed surface, and a disk supported on one of the rotatable members and having a peripheral face engaged with the intermediate portion of the internal surface of said part, planetary gears arranged on opposite sides of the disk, 55 said planetary gears being connected respec-
- tively to the gears revoluble with the driving member and to said second gear, one of the planetary gears being carried by the driven member, means for limiting the rotation of the other planetary gear, and means for limiting the rotation of said second gear, substantially as described.
6. The combination of rotatable driving and driven members, a pair of gears revoluble with the driving member, a second gear revoluble relatively to the driven member and comprising a substantially ring-shaped part formed with an internal-toothed surface, and a disk supported on one of the rotatable members, a support revoluble relatively to the driving and driven members, planetary gears carried respectively by the driven member and the support and arranged on opposite sides of the disk, said planetary gears being connected respectively to the gears revoluble with the driving member and to said second gear, means for limiting the rotation of said second gear, and means for limiting the rotation of the support, substantially as set forth.
7. The combination of rotatable driving and driven members, a pair of gears revoluble with the driving member, a second gear revoluble relatively to the driven member and consisting of a substantially ring-shaped part formed with an internal-toothed surface, a hub, and a disk mounted on the hub, said disk having a peripheral face engaged with the intermediate portion of the internal-toothed surface of the ring-shaped part, a support revoluble relatively to the driving and driven members, a pair of spindles arranged eccentric to the axis of the driven member and supported respectively by the driven member and said support, said spindles being unsupported at their outer ends, planetary gears mounted on the spindles on opposite sides of said disk, each of the planetary gears being connected respectively to one of the gears revoluble with the driving member and to said second gear and said planetary gears having side faces engaged with opposite side faces of said disk for holding the gears in position, means for limiting the rotation of said second gear, and means for connecting the support to the driving member, substantially as and for the purpose specified.
8. The combination of rotatable driving and driven members, power-transmitting means connecting said members, a case having a movable section, said movable section cooperating with the power-transmitting means for controlling the rotation of the driven member, and means for operating said section, substantially as and for the purpose set forth.
9. The combination of rotatable driving and driven members, power-transmitting means connecting said members, a case hav-

ing a bearing-surface substantially concentric with one of said members, and means mounted on the bearing-surface and revolvable relatively thereto for coöperating with the power-transmitting means to control the rotation of the driven member, substantially as described.

10. The combination of rotatable driving and driven members, power-transmitting means connecting said members, a substantially cylindrical case, and means movable about, and lengthwise of, the axis of the case for coöperating with the power-transmitting means to control the rotation of the driven member, substantially as described.

11. The combination of a case provided with an internal hub, rotatable driving and driven members, one of said members being journaled on the hub, and power-transmitting means connecting the driving and driven members, substantially as set forth.

12. The combination of a case provided with an internal hub, a rotatable driving member, a rotatable driven member journaled on the hub, and power-transmitting means connecting the driving and driven members, substantially as and for the purpose set forth.

13. The combination of a case provided with an internal hub, rotatable driving and driven members, the driven member being loosely mounted on the internal hub, a gear revolvable with the driving member, a second gear revolvable relatively to the driven member, a planetary gear revolvable with the driven member and connected respectively to the former gears for transmitting motion to the driven member and means for limiting the rotation of said second gear, substantially as and for the purpose described.

14. The combination of a case provided with an internal hub, rotatable driving and driven members, one of said members being journaled in the hub, and the other being journaled on said hub, and power-transmitting means connecting the driving and driven members, substantially as described.

15. A variable-speed gear having in combination a stationary tubular bearing, a revolvable wheel mounted on the exterior thereof, a revolvable shaft journaled in said bearing, and intervening rotatable means coacting with said shaft and said wheel, substantially as described.

16. The combination of a case provided with an internal hub, a rotatable driving member journaled in the hub, a rotatable driven member journaled on the hub, and power-transmitting means connecting the driving and driven members, substantially as and for the purpose specified.

17. The combination with the frame and crank-shaft of an engine; of a case mounted on said frame and receiving an end of the crank-shaft, a driven member supported

within the case, and power-transmitting means connecting the crank-shaft and the driven member, substantially as set forth.

18. The combination with the frame and crank-shaft of an engine; of a case mounted on said frame and provided with an internal bearing for an end of the crank-shaft, a driven member supported within the case, and power-transmitting means connecting the crank-shaft and the driven member, substantially as set forth.

19. The combination with the frame and crank-shaft of an engine; of a case mounted on said frame and provided with an internal hub forming a bearing for an end of the crank-shaft, a driven member journaled on the hub and power-transmitting means within the case connecting the crank-shaft and the driven member, substantially as set forth.

20. The combination of a case having an opening, a rotatable driving member, a rotatable driven member within the opening, means to close the opening, said means coöperating with the driven member for connecting the driving and driven members, and power-transmitting means connecting the driving and driven members, substantially as and for the purpose specified.

21. The combination of a case having an opening in one of its walls, and an annular groove in the inclosing wall of the opening, rotatable driving and driven members, the driven member projecting into the opening and being formed with a flange, a collar projecting into the annular groove of the case and coöperating with the flange of the driven member to close the portion of said opening not occupied by the driven member, a gear revolvable with the driving member, a second gear revolvable relatively to the driven member, a planetary gear revolvable with the driven member and connected respectively to the former gears for transmitting motion to the driven member, and means for limiting the rotation of said second gear, substantially as and for the purpose set forth.

22. The combination of a case, rotatable driving and driven members supported within the case, power-transmitting means connecting the driving and driven members and including a gear revolvable relatively to the driven member, a split friction-ring between contiguous surfaces of the case and the gear for limiting the rotation of said gear, and means for engaging the friction-ring with the gear, substantially as described.

23. The combination of a case having a removable part, rotatable driving and driven members supported within the case, and power-transmitting means connecting the driving and driven members and including gears mounted on spindles and means for limiting lateral movement of the gears when the removable part of the case is in position, the last-mentioned means being not secured

to the gears or their spindles and being freely detachable therefrom when said part of the case is removed, and the gears being not secured to their spindles and being freely detachable therefrom when said part of the case is removed, substantially as set forth.

24. The combination of a case having a portion thereof formed with an internal hub, said case having a removable part, a rotatable driving member projecting within the case and journaled in the internal hub, a gear detachably mounted on the driving member and revolute therewith, a driven member detachably supported on the internal hub of the case, a second gear revolute relatively to the driven member and detachably mounted on the driving member, and a planetary gear mounted on the driven member and normally detachable therefrom, said planetary gear being connected respectively to the former gears for transmitting motion to the driven member and means for limiting the rotation of said second gear, substantially as and for the purpose described.

25. 25. The combination of rotatable driving and driven members, a gear revolute relatively to the driven member, power-transmitting means between the driving member and the gear for rotating the gear in a direction opposite to that of the driving member, and power-transmitting means between the driven member and the gear for rotating the driven member, substantially as and for the purpose set forth.

35. 26. The combination of rotatable driving and driven members, a gear revolute with the driving member, a second gear revolute relatively to the driven member, a planetary gear revolute with the driven member and connected respectively to the former gears for transmitting motion to the driven member, and means for rotating the second gear in a direction opposite to that of the driving member, substantially as and for the purpose described.

27. The combination of rotatable driving and driven members, a gear revolute relatively to the driven member, a support revolute relatively to the driven member, power-transmitting means mounted on the support and cooperating with the driving member to rotate the gear in a direction opposite to that of the driving member, means for limiting the rotation of the support, and power-transmitting means between the driven member and the gear for rotating the driven member, substantially as and for the purpose specified.

28. The combination of rotatable driving and driven members, a gear revolute relatively to the driven member, a support revolute relatively to the driven member and having one side provided with an engaging surface, power-transmitting means projecting from the other side of the support and co-

operating with the driving member to rotate the gear in a direction opposite to that of the driving member, means cooperating with said engaging surface for limiting the rotation of the support, and power-transmitting means between the driven member and the gear for rotating the driven member, substantially as and for the purpose described.

29. The combination of rotatable driving and driven members, a gear revolute with the driving member, a second gear revolute relatively to the driven member, a support revolute relatively to the driven member, a gear revolute with the support and arranged eccentric to the axis of the driving member, said latter gear cooperating with the first gear for transmitting motion to the second gear, means for limiting the rotation of the support, and means for transmitting motion to the driven member from the second gear, substantially as and for the purpose set forth.

30. The combination of rotatable driving and driven members, a gear revolute with the driving member, a second gear revolute relatively to the driven member, a support revolute relatively to the driven member and having one side provided with an engaging surface, a gear projecting from the other side of the support and revolute therewith, said gear being arranged eccentric to the axis of the driving member and cooperating with the first gear for transmitting motion to the second gear, means for cooperating with said surface and limiting the rotation of the support, and means for transmitting motion to the driven member from the second gear, substantially as and for the purpose described.

31. The combination of rotatable driving and driven members, a gear revolute with the driving member, a second gear revolute relatively to the driven member and formed with an internal-toothed surface, a support revolute relatively to the driven member, a gear revolute with the support and projecting within the second gear, said latter gear cooperating with the first gear for transmitting motion to the second gear, means for limiting the rotation of the support, and means for transmitting motion to the driven member from the second gear, substantially as and for the purpose specified.

32. The combination of a case, rotatable driving and driven members, a gear revolute relatively to the driven member, a support revolute relatively to the driven member, power-transmitting means between the driving member and the gear for rotating the gear in a direction opposite to that of the driving member, said power-transmitting means being mounted on the support and revolute therewith, means between opposing surfaces of the case and the support for limiting the rotation of the support, and power-transmitting means between the driven member and the gear for rotating the driven member substantially as and for the purpose described.

member, substantially as and for the purpose set forth.

33. The combination of a case, rotatable driving and driven members, a gear revoluble with the driving member, a second gear revoluble relatively to the driven member, a support revoluble relatively to the driven member, a gear revoluble with the support and arranged eccentric to the axis of the driving member, said latter gear coöperating with the first gear for transmitting motion to the second gear, means between opposing surfaces of the case and the support for limiting the rotation of the support, and means for transmitting motion to the driven member from the second gear, substantially as and for the purpose set forth.

34. The combination of a rotatable driving member, a gear revoluble with the driving member, a second gear revoluble relatively to the driving member, a support revoluble relatively to the driving member, a gear revoluble with the support and arranged eccentric to the axis of the driving member, said latter gear coöperating with the first gear for transmitting motion to the second gear, and means for limiting the rotation of the support, substantially as and for the purpose described.

35. The combination of rotatable driving and driven members, a gear, means coöperating with the driving member for moving the gear in the same direction as the driving member, means coöperating with the driving member for moving the gear in a direction opposite to that of the driving member, and means for rotating the driven member with the gear, substantially as and for the purpose specified.

36. The combination of rotatable driving and driven members, a gear, means coöperating with the driving member for moving the gear in the same direction as the driving member, means coöperating with the driving member for moving the gear in a direction opposite to that of the driving member, means for limiting the rotation of the gear, and means for rotating the driven member with the gear and for rotating the driven member relatively to the gear when the rotation of the gear is limited, substantially as and for the purpose set forth.

37. The combination of rotatable driving and driven members, a planetary gear revoluble with the driven member and connected to the driving member, a support revoluble relatively to the driven member, a planetary gear revoluble with the support and connected to the driving member, and means coöperating with the planetary gears for moving the driven member in reverse directions, substantially as and for the purpose described.

38. The combination of rotatable driving and driven members, a gear, a planetary gear revoluble with the driven member and con-

nected to the driving member and to the first gear, a support, a gear mounted on the support eccentric to the axis of the driven member and connected respectively to the driving member and the first gear for rotating the first gear in a direction opposite to that of the driving member, substantially as and for the purpose specified.

39. The combination of rotatable driving and driven members, a gear, a planetary gear revoluble with the driven member and connected respectively to the driving member and to the first gear for transmitting motion to the driven member, a support, a planetary gear revoluble with the support and connected respectively to the driving member and to the first gear for rotating said first gear in a direction opposite to that of the driving member, and means for limiting the rotation of the support, substantially as and for the purpose specified.

40. The combination of rotatable driving and driven members, gears of unequal diameter revoluble with the driving member, a single gear revoluble relatively to the driven member, power-transmitting means connected respectively to one of the first gears and to the single gear for transmitting motion to the driven member, means for limiting the rotation of the single gear, and power-transmitting means connected respectively to another of the first gears and to the single gear for rotating the second gear in a direction opposite to that of the driving member, substantially as and for the purpose set forth.

41. The combination of rotatable driving and driven members, gears revoluble with the driving member, a single gear revoluble relatively to the driven member and formed with an internal-toothed surface, a planetary gear revoluble with the driven member and connected respectively to one of the first gears and to the single gear for transmitting motion to the driven member, a support revoluble relatively to the driven member, a planetary gear revoluble with the support and connected respectively to another of the first gears and to the single gear for rotating the second gear in a direction opposite to that of the driving member, and means for limiting the rotation of the single gear and of the support, substantially as and for the purpose described.

42. The combination of rotatable driving and driven members, gears of unequal diameter revoluble with the driving member, a single gear revoluble relatively to the driven member and consisting of a substantially ring-shaped part formed with an internal-toothed surface and a disk arranged within the ring-shaped part between opposite sides thereof and mounted on the driving member, a planetary gear revoluble with the driven member and projecting within the single gear at one side of the disk, said planetary gear

- being connected respectively to one of the first gears and to the single gear for transmitting motion to the driven member, a support revoluble relatively to the driven member, a planetary gear revoluble with the support and projecting within the single gear at the other side of the disk, said second planetary gear being connected respectively to another of the first gears and to the single gear for rotating the second gear in a direction opposite to that of the driving member, and means for limiting the rotation of the single gear and of the support, substantially as and for the purpose specified.
43. The combination of rotatable driving and driven members, a support movable relatively to the driving member and having one side provided with a projecting flange, a second support arranged within the flange of the first support and revoluble with the driving member, a split friction-ring supported upon the outer face of the second support within the flange, an expander supported upon the outer face of the second support for forcing the friction-ring into its operative position, and power-transmitting members connecting the driving and driven members, some of the power-transmitting members being mounted on the first-named support, substantially as and for the purpose set forth.
44. The combination of rotatable driving and driven members, a support movable relatively to the driving member and having one side provided with a projecting flange, a second support arranged within the flange of the first support and revoluble with the driving member and having its outer side provided with a spindle and an engaging arm arranged substantially opposite to each other and within said flange, a split friction-ring within the flange having a cut-out for receiving the engaging arm of the second support, an expander pivoted on the spindle of the second support and movable between the separated ends of the friction-ring, means projecting within the flange of the first support for actuating the expander, and power-transmitting members connecting the driving and driven members, one of said power-transmitting members being mounted on said first-named support, substantially as and for the purpose described.
45. The combination of a case, driving and driven members within the case, power-transmitting means within the case, means for locking the driving member to the power-transmitting means, and a cam supported by the case and movable relatively thereto for forcing said means into its operative position, substantially as and for the purpose specified.
46. The combination of a case comprising a main body having an opening therein, a movable section journaled on the main body and provided with a cam projecting into the case through said opening, means for forcing the movable section endwise during the movement thereof on its axis, rotatable driving and driven members within the case, a pair of supports within the case, one being revoluble relatively to the driving member and the other being revoluble with the driving member, power-transmitting means for connecting to the driven member the support revoluble relatively to the driving member, friction means for connecting the supports, said means being normally in its inoperative position, and means actuated by said cam for forcing the friction means into its operative position, substantially as and for the purpose set forth.
47. The combination of a case having a removable part, a rotatable driving member projecting within the case, power-transmitting means detachably mounted on the driving member and revoluble therewith, the parts of said means being detachable from each other, a pair of supports detachable from each other and detachably supported on the driving member, one support being revoluble relatively to the driving member and the other being revoluble with said driving member, a second power-transmitting means detachably connected to one of the supports and to the driven member, the parts of the second power-transmitting means being normally detachable from each other, and means for locking the supports together, the parts of the latter means being also normally detachable from each other, substantially as and for the purpose described.
- In testimony whereof I have hereunto signed my name, in the presence of two attesting witnesses, at Syracuse, in the county of Onondaga, in the State of New York, this 16th day of July, 1902:

JOHN WILKINSON.

Witnesses:

S. DAVIS,
D. LAVINE.
